CLAIM

The ornamental design for a carabiner with strap attachment, as shown and described.

DESCRIPTION

FIG. 1 is a front plan view of a first embodiment of a carabiner with strap attachment. The gate, strap, pin holes and lever, which are shown in intermittent broken lines, represent environmental subject matter and form no part of the claim.

FIG. 2 is a rear plan view of FIG. 1.

FIG. 3 is a right side elevation view of FIG. 1.

FIG. 4 is a left side elevation view of FIG. 1.

FIG. 5 is a top elevation view of FIG. 1.

FIG. 6 is a bottom elevation view of FIG. 1.

FIG. 7 is a rear perspective view of FIG. 1.

FIG. 8 is a rear plan view of a second embodiment of a carabiner with strap attachment. The right side elevation view is a mirror image of FIG. 3. The left side elevation view is a mirror image of FIG. 4. The gate, strap, pin holes and lever, which are shown in intermittent broken lines, represent environmental subject matter and form no part of the claim.

FIG. 9 is a front plan view of FIG. 8.

FIG. 10 is a top elevation view of FIG. 8; and,

FIG. 11 is bottom elevation view of FIG. 8.
